UNITED STATES PATENT OFFICE.

FREDERIC V. HETZEL, OF PHILADELPHIA, PENNSYLVANIA, ASSIGNOR TO THE LINK BELT ENGINEERING COMPANY, OF PHILADELPHIA, PENNSYLVANIA, A CORPORATION OF PENNSYLVANIA.

CAR-HAUL.

SPECIFICATION forming part of Letters Patent No. 761,484, dated May 31, 1904.

Application filed March 7, 1903. Serial No. 146,705. (No model.)

To all whom it may concern:

Be it known that I, FREDERIC V. HETZEL, a citizen of the United States, residing in Philadelphia, Pennsylvania, have invented certain 5 Improvements in Car-Hauls, of which the following is a specification.

My invention relates to certain improvements in car-hauls used for transferring a car from the pit-opening of a mine or other lower 10 level to an elevated point, where the car is unloaded.

The main object of my invention is to decrease the strain upon the drive-chain of the car-haul without lessening the output of the 15 plant. This object I attain by increasing the speed of the chain on the inclined plane.

A further object of my invention is to increase the speed of the main drive-chain and allow the chain to engage the car without 20 due shock. This object I attain by providing an auxiliary chain which is driven at the ordinary speed, so that it will engage the car and set it in motion and so that the car will be under way when the main chain, which is 25 driven at a higher speed, engages it.

Car-hauls as ordinarily constructed consist of an inclined track, upon which the car-wheels travel, and an endless chain having lugs arranged to engage a car. The speed of 30 the chain is limited, owing to the fact that the chain must engage the car at the base of the inclined plane and carry it up to the discharge-point, and if the chain is traveling at too high a speed the shock will be so great as 35 to not only affect the machinery, but injure the car or cause it to jump the track; but when the car is once on the inclined plane the speed of the chain can be materially increased without any bad effect.

40 In the accompanying drawings, Figure 1 is a side view of the base portion of a car-haul, illustrating my invention. Fig. 2 is a plan view of Fig. 1. Fig. 3 is a transverse sectional view on the line 3 3, Fig. 1, looking in 45 the direction of the arrow; and Fig. 4 is a diagram view of a modification.

A A are the rails of the track, mounted on suitable ties a a in the usual manner. The

lower portion of the track is usually straight and connects with the track from the mine. 50 The inclined portion of the track extends to any height desired.

B is the main drive-chain, which passes around a sprocket-wheel C on the main shaft E, mounted in bearings e e. As shown in 55 Fig. 2, the chain is situated midway between the tracks A A and has lugs or projections b, which engage a portion of the car. The chain can be of any type desired without departing from the main feature of my invention. 60

G is a coal-car of the ordinary type having flanged wheels g g, which travel on the rails A A, and depending from the center portion of the car in the present instance are brackets i, carrying a bar i', with which one of the 65 lugs b of the main chain B engages. By placing the bar in the position shown the jolting or other motion of the car will not disengage the car from the lug b, as it is at the point of least motion. 70

D is an auxiliary chain passing around a sprocket-wheel C' on the shaft E and around a sprocket-wheel F, some distance from the shaft E. This wheel is secured to a shaft F', mounted in bearings f f. The chain also passes around 75 an idler C² on the shaft E', mounted in bearings e' e'. The bearings for the shafts E, C², and F' are preferably adjustable.

In the drawings I have shown the sprocket-wheel C' one-half the diameter of the sprocket-wheel C, so that the chain D travels at one-half the speed of the chain B. The idler C² is placed in the position shown to elevate the chain D and keep its upper run in the proper line with the rails A, so that the lug d on the chain will engage the bumper h on the end of the car G. 80

It will be understood that the relative diameters of the sprocket-wheels C and C' will vary according to the speed of the shaft and 90 the desired speed of the chains.

It will be noticed in the drawings that in the present instance there is only one lug d on the chain D, and this is so arranged in respect to the lugs b on the main drive-chain B 95 that the lugs b will engage the car before the

lug d disengages it, so that from the moment the car starts it is under the complete control of the chains.

If desired, the chain D may have more than 5 one lug d , in which case the length of the chain will be increased or the lugs on the main carrying-chain would be arranged closer together.

While I have shown in Fig. 1 only one auxiliary chain, which is driven at half the speed of the main drive-chain, there may be two or more auxiliary chains, as shown in the diagram Fig. 4, which illustrates two auxiliary chains D and D', the chain D' being driven 15 from a wheel F' on the shaft F'.

In place of the chains shown ropes may be used having projections or lugs secured to them in any suitable manner; but I prefer to use the drive-chain shown.

20 The supporting structure may be constructed in any manner, and I have not entered into the details of this, as any suitable supporting structure can be used.

By the above construction it will be seen 25 that the speed of the main chain B can be increased to double the ordinary speed of the chain by placing the car in motion by means of the auxiliary chain D before the main chain B engages it. Thus the same number of cars, 30 or even more, can be delivered at the top of the car-haul with a less number of cars on the inclined plane, and consequently the strain on the chain is decreased, and in some instances a lighter chain can be used than heretofore.

35 While I have shown the auxiliary chain D driven from the same shaft as the main chain B, it will be understood that separate driving mechanism may be used, if desired; but I prefer the construction shown, as it simplifies the 40 drive.

I claim as my invention—

1. The combination in a car-haul, of a track, 45 a main drive-chain and an auxiliary drive-chain, each having lugs, sprocket-wheels for the said chains, a shaft on which two of said sprocket-wheels are mounted and through which motion is imparted from one chain to the other, substantially as described.

2. The combination in a car-haul, of the 50 track, a main drive-chain, a shaft, a sprocket-wheel mounted on the shaft around which the main chain passes, a lug on the main chain arranged to engage a car, a sprocket-wheel on said shaft less in diameter than the main

sprocket-wheel, an auxiliary drive-chain passing around the said small sprocket-wheel and having a lug arranged to engage the car so that the car will be first set in motion by the auxiliary chain and will be transferred by it to the main chain, substantially as described. 55

3. The combination of a track upon which travels the car to be propelled, a shaft, two sprocket-wheels on the shaft one sprocket-wheel being less in diameter than the other, a main drive-chain passing around the larger 60 sprocket-wheel and having a series of lugs which engage the car, with an auxiliary chain passing around the small sprocket-wheel and having a lug engaging the car, the main chain 65 extending upward between the inclined tracks and the auxiliary chain extending between the horizontal tracks, the lugs of the chains being so arranged that the car will be set in motion by the auxiliary chain and transferred to the main chain which is driven at a greater 70 speed, substantially as described.

4. The combination in a car-haul, of the 75 horizontal and inclined tracks, a driving-shaft having two sprocket-wheels thereon, one of greater diameter than the other, a main drive-chain mounted between the inclined tracks 80 passing around the large sprocket-wheel and having one or more lugs thereon, an auxiliary chain passing around the small sprocket-wheel and extending around the horizontal 85 portion of the track, a car mounted on the track, a central bar on the car and a bumper on the car, the lug on the auxiliary chain engaging the bumper and the lug on the main chain engaging the bar before the lug on the auxiliary chain leaves the bumper of the car, 90 substantially as described.

5. The combination in a car-haul, of a track, 95 a main drive-chain and an auxiliary drive-chain, sprocket-wheels for the chains, a shaft, two of the sprocket-wheels mounted on said shaft, the sprocket-wheel for the auxiliary chain being less in diameter than the wheel for the main chain, and an idler for guiding the auxiliary chain, substantially as described. 100

In testimony whereof I have signed my name to this specification in the presence of two subscribing witnesses.

FREDERIC V. HETZEL.
